(Cl. D56—1)

FIG. 1.

FIG. 2.

FIG. 3.

FIG. 4.

FIG. 5.

FIG. 6.

FIG. 1 is a left side and top perspective view of a stringed musical instrument, showing my new design;

FIG. 2 is a top plan view;

FIG. 3 is a top and right side perspective view;

FIG. 4 is a right side elevational view;

FIG. 5 is a bottom and right side perspective view; and

FIG. 6 is a bottom plan view thereof.

The characteristic feature of my design resides in the bridge structure extending to the rounded base of the body of the instrument and the vibrator unit extending along the entire lower side of the body of the instrument as shown particularly in FIG. 2.

I claim:

The ornamental design for a stringed musical instrument, substantially as shown and described.
